UNITED STATES PATENT OFFICE.

GEORGE HENRY JOHNSON, OF HATTIESBURG, MISSISSIPPI.

MEANS FOR PREVENTING CLOGGING OF SAND-PIPES.

1,341,236.

Specification of Letters Patent. Patented May 25, 1920.

Application filed October 18, 1919. Serial No. 331,544.

To all whom it may concern:

Be it known that I, GEORGE HENRY JOHNSON, a citizen of the United States, and a resident of Hattiesburg, in the county of 5 Forrest and State of Mississippi, have invented certain new and useful Improvements in Means for Preventing Clogging of Sand-Pipes, of which the following is a specification.

10 My present invention relates generally to sand pipes of steam as well as street rail-ways, and it primary object is the provi-sion of simple, inexpensive means to pre-vent the clogging of sand pipes, particularly 15 at or adjacent to the discharge end of the pipe, where clogging commonly occurs at the present time.

In carrying out this object my invention proposes the use of an air supply attach-20 ment under control of the operator, for in-stance a locomotive engineer or a street rail-way motorman, this attachment being used in such a way as to accomplish another ob-ject of the invention, which is to direct the 25 sand exactly where it is desired and most useful, in spite of the influence of wind or other exterior force.

In the accompanying drawing illustrating 30 my present invention, and forming a part of this specification,

Figure 1 is a side view showing the practical application of my invention, and

Fig. 2 is an enlarged central vertical sec-tion through the discharge end of the said 35 pipe.

Referring now to these figures, and parti-cularly to Fig. 1, I have indicated a sand 40 pipe generally at 10, the discharge end 11 of which is slightly angular in order to di-rect the sand into the crotch of a wheel, to the point where it is desired, although this delivery of sand is often impeded, as at present utilized, by wind or other exterior influence.

45 According to my improvement, I utilize an air supply pipe 12 which may lead from the main air drum, and which has an angular fitting 13 extending into and through the wall of the pipe 10, with a terminal nozzle 14 directed toward the discharge end 11 of the sand pipe and, as best seen in Fig.

2, located adjacent to the said discharge end and in the axial line of the pipe.

Sand pipes very often become clogged at or near the extreme discharge end owing to 55 moisture, snow and ice, and in addition to directing the sand under pressure to the points where it is desired, my improved at-tachment will provide effective means for maintaining the discharge end of the pipe 60 free and open at all times.

In case the discharge end of the pipe is clogged with ice and considerable pressure required for the dislodgment of this ice through the nozzle 14, it is preferable that 65 the sand pipe shall also have an air outlet pipe 15, one end of which is connected to the sand pipe at a point farther removed from the discharge end 11 thereof as compared to the nozzle 14, thus allowing the high pres-70 sure derived from pipe 12 to find ready es-cape when it collects within the sand pipe previous to dislodgment of the ice by the air blast.

The supply of air to the pipe 12 is con-75 trolled in any suitable manner as by means of a control and cut off valve 16, which is normally closed and which in practice may be located within a locomotive cab, or in other words, under ready control of the op-80 erator.

I claim:—

1. The combination with a sand delivery pipe, of an air nozzle located therein adja-85 cent to its discharge end, and directed to-ward said discharge end, a valved air sup-80 ply pipe communicating with said nozzle, and a pressure exhausting pipe having com-munication at one end with the said sand 90 pipe at a point farther removed from the discharge end than the said nozzle.

2. The combination with a sand delivery pipe, of an air nozzle located therein and directed toward the discharge end of the pipe, air supply means in communication 95 with said nozzle, and a pressure exhausting connection leading from the sand pipe and opening exteriorly thereof at a point farther removed from the discharge end of the pipe than the said air nozzle.

GEORGE HENRY JOHNSON.
